UNITED STATES PATENT OFFICE.

ALFRED W. ROWLEY AND FRANK H. RYDER, OF COBLESKILL, NEW YORK, ASSIGNEES
TO HARDER MANUFACTURING CORPORATION, OF COBLESKILL, NEW YORK, A COR-
PORATION OF NEW YORK.

REFRIGERATOR-DOOR CONSTRUCTION.

Application filed July 15, 1922. Serial No. 575,329.

To all whom it may concern:

Be it known that we, ALFRED W. ROWLEY and FRANK H. RYDER, both citizens of the United States, and residing at Cobleskill, in the county of Schoharie and State of New York, have invented certain new and useful Improvements in Refrigerator-Door Construction, of which the following is a specification.

10 This invention relates to refrigerator doors and to a method of making the same, and more particularly relates to a refrigerator door having a pan on the rear side thereof, to a method of mounting the door pan upon such door, and to a method of assembling the door.

One of the aims of this invention is to provide a refrigerator door which may be constructed cheaply and quickly, and one which is durable and serves its intended purpose efficiently. A further object of this invention is to provide a method whereby a refrigerator door having a pan on its rear side may be quickly and cheaply constructed 25 and assembled, and another object of this invention is to provide improved means for securing the pan in place on the door. Other objects will be in part obvious and in part pointed out hereinafter.

30 In accordance with this invention, the door includes an outer portion large enough to cover the door opening, and a marginally flanged pan mounted on and secured to the rear side of the outer portion, or to a frame 35 formed or secured thereon, by means of metal retaining strips which are secured to the outer portion, or to the frame portion, and which have marginal inturned flanges overlapping and interlocking with the 40 flanges of the pan. Preferably the flanges of the pan are slidable in the grooves provided by the retaining strips, so that when one of the retaining strips is removed from the door, the pan may be placed in position 45 on the door or removed therefrom by a sliding movement. When the pan has been slid in this manner into position on the door, the absent retaining strip may be easily adjusted into position with its flange portion 50 overlapping and interlocking with the unengaged flange of the pan, and the strip may then be secured to the outer door portion or to the frame thereon, or, if the strip is carried on an unsecured frame member,

this frame member may be adjusted and secured in proper position on the door.

The invention accordingly consists in the features of construction, combinations of elements, and arrangement of parts, which will be exemplified in the construction hereinafter set forth and in the several steps, and the relation to each of the others thereof which will be exemplified in the herein-after disclosed method, and the scope of the application of the invention will be indicated in the claims that follow.

In order that a clearer understanding of this invention may be had, attention is hereby directed to the accompanying drawings, forming a part of this application, and illustrating several possible structural embodiments of this invention, and several various methods of construction and assembly. Referring to the drawings, Fig. 1 is an elevation of the rear side of a door embodying our invention, certain parts being broken away in order to more clearly bring out details of the construction; Fig. 2 is a section of a portion of the door, and is taken on the line 2—2 of Fig. 1; Fig. 3 is a perspective view of the pan portion of the door detached therefrom; Fig. 4 is a plan view of a form useful in assembling the door; Fig. 5 is a plan view showing how the form is used to locate frame members on the outer door portion; Fig. 6 is a plan view of a shield useful in assembling the door, and shows how the retaining strips are associated therewith; Fig. 7 is a plan view showing how the shield and the form serve in assembling together the frame portions, the retaining strips, and the outer door portion; Fig. 8 is a plan view showing the shield and one frame member and retaining strip removed to permit of the application of the door pan; and Fig. 9 is a sectional view of a portion of the assembly shown in Fig. 7, and is taken on the line 9—9 thereof. Similar reference characters refer to similar parts throughout the several views of the drawings.

Referring to the embodiment of the invention illustrated in the drawings, the door comprises an outer portion 1, adapted to cover a door opening, and may also comprise a flange portion 2, which is adapted to marginally overlap a wall about such door opening when the door is closed, and a rabbet

portion 3, which is adapted to snugly fit within the periphery of a door opening when the door is closed, and, if desired, paneling 4. If desired, insulating medium, such as 5 waterproof paper 5, may be glued to or be otherwise secured over a portion of the inner surface of the portion 1.

As shown in the drawings, the rear side 10 of door portion 1 carries a rectangular frame, which may be formed as an integral part of portion 1, although preferably this frame is built up of the positioning strip 15, the inner sheet of insulating material 12 and the four separate frame members or moulding 15 strips 6 which are secured to door portion 1 by means of glue, nails or other suitable means. Frame members 6 are adapted to extend within a door opening when the door is closed. A pan 7, preferably metallic, 20 and having marginal flanges 8, is supported and held in place on frame members 6 by means of metal retaining strips 9, which are secured to frame members 6 by means of nails 10, or the like, and which have marginal in- 25 turned flanges 11 overlapping and interlocking with the marginal flanges 8 of the pan 7. Preferably the flanges 8 of the pan 7 are slideable in the grooves provided by the flanges 11 of the retaining strips 9, so that 30 when one of the retaining strips 9, or a frame member 6 with its retaining strip 9 thereon, is removed from the door, the pan 7 may easily and quickly be placed in position on the door or be removed therefrom by 35 sliding the pan into or out of the grooves of the positioned strips 9. By this means a rigid and durable construction is obtained, and the pan is securely and firmly held in place on the door. If desired, there may be 40 placed in the pan a suitable insulating device. The feature of having a refrigerator door sound-proof is very desirable, since a metal door that produces a tin-like sound when struck creates an unfavorable impression upon a purchaser. To avoid this sound 45 the insulating device may be constructed of one or more wooden members 13 on each side of which are secured, as by means of glue, or nails 14, or the like, one or more resilient 50 sheets 12 of insulating material, such as jute board. The insulating device is made to be a trifle thicker than is the depth of the pan, so that the device presses uniformly against the adjacent surface of the pan; and prevents 55 the pan from producing the objectionable tin-like sound when struck. The insulating device may be held in place by means of a reinforcing and positioning strip 15 placed 60 on the rear side of the door portion 1, and by means of portions 16 of strips 9, which extend interiorly of frame members 6, the insulating device being held firmly against the pan, centrally by strip 15 and marginally by portions 16. This invention, how- 65 ever, is not limited to a door having an in-

sulating device, nor to the insulating device specifically described.

Many different methods of assembling the door may be followed. For instance, three of the moulding strips 6 with their retaining strips 9 are secured in proper position on the door member 1. Then the opposite flanges of pan 7 are inserted in the corresponding opposite grooves provided by opposite mounted strips 9 and the pan is slid 75 into position with its flanges 8 on three sides interlocking with the flanges 11 of the mounted retaining strips 9. Then the fourth moulding piece 6 with its retaining strip 9 is adjusted into proper position so that the flange 11 of this strip overlaps and interlocks with the flange on the unengaged side of pan 7, and this strip 9 is then secured in place, as by means of nails 17, or by means of glue or the like. Obviously, 80 this last moulding piece 6 may be secured to the outer member 1 before the pan is slid into position, if its retaining strip is removed, and in this event this retaining strip 9 may be adjusted and secured in place on 85 this moulding strip as the final operation in the assembly of the door. The insulating paper 5, reinforcing strip 15 and the insulating material 12 should be assembled 90 into the construction before pan 7 is slid into final position, if these elements are desired. From the above it will be apparent that our improved method permits of the construction of a durable and efficient 95 refrigerator door quickly and cheaply.

It is also possible to assemble the doors quickly and cheaply, and to secure the proper relative adjustment and positioning of the various component parts by means of a method which involves the use of a form 100 and a shield. The form 18 serves to locate the molding strips 6 in their proper position on the door portion 1, and the shield 19 serves to locate the retaining strips 9 in their proper positions on the frame members 6. For assembling a rectangular door, the form 18 has a rectangular opening, and its inner periphery has surfaces 20 against which the outer periphery of the door portion 1 is adapted to come, and the inner periphery of the form 18 also has surfaces 21 which serve to locate the molding strips 6 in proper position on the outer door portion 1. The shield 19 comprises a rectangular sheet of suitable material, such as sheet metal, slightly thicker than the thickness of the pan flanges 8. The shield or plate 19 serves to locate retaining strips 9 carried on the edges of this shield in proper position on the frame members 6. In accordance with this method, the outer door portion 1 is located in the form 18. Then molding strips 6 are placed on the inner surface of the portion 1 with their outer edges in contact with the surfaces 21 of the frame 18. Molding strips 9 are lo- 110 115 120 125 130

cated on the edges of the shield or plate 19, and the shield or plate 19 with these strips 9 is then placed upon the frame members 6 as shown in Fig. 7. Shield 19 is supplied 5 with suitable holes 22 to locate nails. Long nails 23 are driven through holes 22, through strips 9, through frame members 6, and into the outer door portion 1 but on three sides only. Shorter nails 24 are driven through 10 the holes 22 and the strip 9 and into its frame member 6 on the remaining side, but these nails 24 do not go into the outer door portion 1. Loose frame member 6 is then removed, carrying with it strip 9 attached 15 thereto by means of the nails 24. Shield 19 is then slid out from the retaining strips 9. The pan 7 is now slid into place on the door, and the unsecured molding piece 6 adjusted and secured to the door by means of nails 17 20 as in the method described in the preceding paragraph. When the shield, which is a trifle thicker than the pan flanges, is removed, the pan may be easily slid into the grooves of the secured retaining strips 9, 25 In every case of attaching members, except metal members 9, glue may be used as well as nails or screws or the like. The form 18 and the door may be separated at any time after three of the strips 6 have been secured 30 in position.

As many changes could be made in the above construction and method, and as many apparently widely different embodiments of this invention could be made without departing 35 from the scope thereof, it is intended that all matter contained in the above description or shown in the accompanying drawings shall be interpreted as illustrative and not in a limiting sense.

40 What we claim is:—

1. A door, comprising, in combination, an outer portion, a frame on the rear side of said outer portion adapted to form a dead-air space, and a pan mounted on said frame 45 by means of metal retaining strips on said frame and having flanges interlocking with flanges on the pan.

2. A door, comprising, in combination, an outer portion, a frame on the rear side of said outer portion adapted to form a dead-air space, and a pan mounted on the rear of said frame by means of metal retaining strips secured to the rear side of said frame, and having flanges interlocking with flanges 55 on the pan.

3. A door, comprising, in combination, an outer portion, moulding strips secured to the rear side of said outer portion and forming a rectangular frame, a metal retaining strip secured to each of said moulding strips, a pan having marginal flanges, and marginal inturned flanges on said retaining strips overlapping and interlocking with the flanges of said pan.

46 4. A door, comprising, in combination, an

outer portion, moulding strips secured to the rear side of said outer portion and forming a rectangular frame, a metal retaining strip secured to the rear face of each of said moulding strips, a pan having marginal flanges continuous around the corners and forming a continuous encircling flange, and marginal inturned flanges on said retaining strips overlapping and interlocking with the flange of said pan. 70

5. A door, comprising, in combination, an outer portion, a frame on the rear side of said outer portion, a pan mounted on said frame by means of metal retaining strips secured to the rear side of said frame and 80 having flanges interlocking with flanges on the pan, insulating material within said pan, and portions of said retaining strips extending inwardly of said frame, overlapping said insulating material, and retaining said material within the pan. 85

6. In a door, the combination with an outer portion, a frame on the rear side of said outer portion having a covering adapted to form a dead-air space and a pan thereon, of 90 insulating and sound deadening means associated therewith, said means comprising resilient insulating material pressing uniformly over the under surface of said pan whereby a second air space is provided. 95

7. In a door, the combination with a pan thereon, of an insulating and sound-regulating device within said pan, said device comprising a wooden member and a sheet of resilient jute board secured to each side of 100 said member, said device being thicker than the depth of the pan, and means, comprising members on said door and beneath said device, pressing said device against the under surface of said pan. 105

8. The method of mounting a marginally flanged pan upon a door by means of a plurality of retaining strips having flanges adapted to slidably interlock with the pan flanges, which consists of securing less than 110 the whole number of said retaining strips in position on the door, engaging flanges of the pan with flanges of retaining strips secured on the door, sliding the pan into position on the door, adjusting each unsecured retaining strip into position of engagement with a pan flange, and securing each unsecured strip in position on the door. 115

9. The method of mounting a marginally flanged pan upon a door by means of four frame members, each carrying a retaining strip providing a flange adapted to slidably interlock with a pan flange, which consists of securing three of said frame members in position on the door, engaging flanges of 120 the pan with flanges provided by retaining strips carried on secured frame members, sliding said pan into position on said door with flanges thereof interlocking with the flanges of the retaining strips carried by the 13

three secured frame members, adjusting the fourth and unsecured frame member with its retaining strip into position, with the flange of its retaining strip interlocking with 5 a flange of said pan, and securing said fourth frame member to said door.

10. The method of mounting a marginally flanged pan upon a door, which consists of locating frame members on the rear side of 10 said door by means of a form, locating retaining strips on said frame by means of a shield, securing said retaining strips to said frame members and some of said frame members to the door, removing one of said 15 frame members with its retaining strip, removing the shield, positioning a pan on said

door in engagement with said positioned retaining strips, and adjusting and securing said unsecured frame member with its retaining strip in place on the door and in engagement with said pan. 20

11. A device for assembling frame members with an outer door portion, which comprises a form having means for locating an outer door portion in fixed relation to said 25 form and providing means for locating frame members in fixed relation to said form and door portion.

This specification signed this 11 day of July, 1922.

ALFRED W. ROWLEY.
FRANK H. RYDER.
